UNITED STATES PATENT OFFICE

LEON E. SIMMONS, OF CLAREMONT, NEW HAMPSHIRE, ASSIGNOR TO SULLIVAN MACHINERY COMPANY, A CORPORATION OF MASSACHUSETTS

LUBRICATING SYSTEM

Application filed September 6, 1927, Serial No. 217,745, and in Great Britain August 9, 1927.

My invention relates to lubrication systems and more particularly to lubrication systems especially adapted to use in mining machines of the electrically propelled type.

5 In modern, very low mining machines in which electric motor drive is employed and in which by reason of the very low height of the machine the gearing necessarily fills substantially the whole of the vertical height of the 10 machine, difficulty has been encountered due to the fact that lubricant providing a bath for the gearing and maintained at a sufficient level to successfully lubricate the same stands at a higher level in the casing than the lowest 15 point in the armature shaft, with resultant possibility of leakage of lubricant into the motor around and along the shaft and so injury to the windings of the motor.

It is an object of the present invention to 20 provide an improved arrangement whereby in any, and particularly in a low and compact mining machine access of oil to the motor windings of an electric driving motor may be prevented. It is a further object of 25 the invention to provide improved means whereby a high lubricant level may be maintained in the gearing chamber of a mining machine while avoiding the possibility of injury to the windings of a motor which activates the gearing. Other objects and advantages of the invention will subsequently appear.

In the accompanying drawings, in which I have shown for purposes of illustration one 30 embodiment which the invention may assume in practice,

Fig. 1 is a plan view, with parts omitted and other parts shown in dotted outline, of a mining machine in which the illustrative embodiment of this invention is incorporated.

Fig. 2 is a combined side elevation and sectional view of the feed end of the mining machine shown in Fig. 1.

Fig. 3 is a plan view on enlarged scale with parts broken away to show details in section of such mining machine.

Fig. 4 is a section on the line 4—4 of Fig. 3.

Fig. 5 is a detail in plan.

Fig. 6 is a central section on the line 6—6 of 50 Fig. 5.

Fig. 7 is a view taken on line 7—7 of Fig. 5.

Referring to the drawings, a mining machine generally designated 1 and comprising a motor section 2, a cutter section 3, and a feed section 4 is shown in Fig. 1. The motor section 2 contains an electric motor having an armature 5 which drives through suitable gearing a cutter chain 6, which constitutes the cutting device of the mining machine and which is supported for orbital movement 45 upon a cutter bar 7. The machine is propelled and the cutter bar swung by feed mechanism, which is enclosed in the section 4 and which effects the functions stated with the aid of a feed chain 9.

It is highly important for the proper operation of the feeding mechanism to provide proper lubrication for the gearing. The feed section 4 comprises two gearing enclosing compartments 10 and 11, the former containing most of the gearing and the latter containing certain initial driving elements of the gearing. The gearing need not be shown in detail as it is, per se, not my invention, being the invention of one Morris P. Holmes and covered in his application Ser. No. 136,446, but it may be noted that the motor armature 5 is mounted upon a shaft 12 which supports a driving pinion 13, pinion 13 meshes with and drives a larger gear 14 on a stud 14^a, 70 while the gear 14 drives a gear 15 mounted on a shaft 16 and driving a bevel pinion 17. Shaft 16 extends through the wall between chambers 11 and 10. The bevel pinion 17 drives a bevel gear 18 which effects rotation 75 of a worm 19 mounted upon a shaft 20. The gear elements 17, 18 and 19 and all the remaining elements of the feed gearing are enclosed in the chamber 10 while the pinion 13 and the gears 14 and 15 are enclosed in the 80 chamber 11.

It is found desirable in practice to have a lubricant level in the chamber 10 above the horizontal plane in which the bottom of the armature shaft 12 lies, but obviously, even though a leather or other suitable packing means 21 is provided to preclude flow of oil from the chamber 11 longitudinally of the armature shaft and so into the motor casing, there would be serious danger 85 of injury to the motor if the oil level were to 90 95 100

be permitted to stand in the chamber 11 above the level of the bottom of the ring 21. To minimize entrance of oil to the chamber 11 from the chamber 10 around the shaft 16 a 5 leather washer 22 is placed to the inside of gear 17, but while this is quite effective it is not absolutely certain, and so it is essential to provide for the removal of the oil from the chamber 11 as rapidly as it enters. This is 10 effectively accomplished by the coaction of the gear elements 13, 14 and 15 and a spout element 23 which is supported in the wall 24 separating a part of the chamber 10 from the chamber 11, the spout having an opening 15 through which the oil may be discharged and a flattened, wide, straight mouth 26 to receive oil. The gear elements 13, 14 and 15 pick up lubricant with their lateral edges, and irrespective of the direction of motor rotation, lubricant is thrown to the top wall 24^a of the chamber 11 from which it falls upon or is discharged into the mouth of the spout 23. As a result even with the oil level in the casing or chamber 10 above the central horizontal plane of the machine, the oil in the chamber 11 is constantly maintained at a level approximately as shown at 27 in Fig. 4. Suitable auxiliary provision for protecting the motor and discharging oil which might succeed in passing along the shaft 12 is provided and is shown in part at 28 in Fig. 2, but since the oil level is maintained below the base of the ring 21 at all times when the motor is running, the danger of injury to the motor is 30 greatly reduced.

From the foregoing description it will be evident that when the motor is running, oil which passes into the chamber 11 is picked up by the gear 15 and if the oil level be high 40 enough when the motor is started, also by the gear elements 13 and 14 and transferred from one to another until it reaches top wall 24^a of the chamber 11, from which it enters, and is discharged by means of, the spout 23 into the chamber 10 and so precluded from securing access to the motor housing 2. As a 45 result of this improvement, a much more perfect safeguard against oil is provided and a longer life and freedom from interruption 50 in operation of the motor is secured.

While I have in this application specifically described one form which my invention may assume in practice, it will be understood that this form of the same is shown for purposes 55 of illustration and that the invention may be modified and embodied in various other forms without departing from its spirit or the scope of the appended claims.

What I claim as new and desire to secure 60 by Letters Patent is:

1. In an apparatus of the character described, a motor housing containing a motor having a power shaft, a gear housing adjacent said motor housing and containing in- 65 termeshing gearing driven by said motor and

a lubricant for the gearing, and means for precluding entry of lubricant from said gear housing to said motor housing including a relatively small lubricant containing compartment in the gear housing spaced from the main interior portion thereof and into which the motor power shaft projects, said compartment containing a portion of the gearing and the gearing in said compartment driving the gearing in the main interior portion of said gear housing, means for supplying lubricant to said small compartment, and means for automatically discharging lubricant from said small compartment into the main interior portion of said gear housing and including lubricant discharge means adjacent the top of said small compartment. 70 75 80

2. In an apparatus of the character described, a motor housing in which a motor having a power shaft is disposed, a gear housing adjacent said motor housing, the interior of said gear housing being divided into a main gear chamber and an initial gear chamber and said initial gear chamber being adjacent the motor housing with the power shaft of the motor projecting thereinto, the initial gear chamber containing intermeshing gearing driving the gearing in said main chamber and said chambers containing a lubricant for the gearing, means for supplying lubricant to said initial gear chamber, and means for maintaining a lubricant level in said initial gear chamber below the bottom of the motor power shaft including certain gears in said initial gear chamber driven by said power shaft and throwing lubricant, and means disposed in the same vertical plane with said lubricant throwing gears for receiving the lubricant so thrown and conveying it into the main gear chamber. 90 95 100 105

3. In an apparatus of the character described, a motor housing in which a motor having a power shaft is disposed, a gear housing adjacent said motor housing, the interior of said gear housing being divided into a main gear chamber and an initial gear chamber and said initial gear chamber being adjacent the motor housing with the power shaft of the motor projecting thereinto, the initial gear chamber containing intermeshing gearing driving the gearing in said main chamber and said chambers containing a lubricant for the gearing, means for supplying lubricant to said initial gear chamber, and means for maintaining a lubricant level in said initial gear chamber below the bottom of the motor power shaft including certain gears in said initial gear chamber driven by said power shaft and throwing lubricant, and means for receiving the lubricant so thrown and conveying it into the main gear chamber, said lubricant receiving and conveying means including a spout in the same vertical plane with the lubricant throwing gears. 110 115 120 125

4. In an apparatus of the character de-

- scribed, a motor housing in which a motor having a power shaft is disposed, a gear housing adjacent said motor housing, the interior of said gear housing being divided into a main gear chamber and an initial gear chamber and said initial gear chamber being adjacent the motor housing with the power shaft of the motor projecting thereinto, the initial gear chamber containing intermeshing gearing driving the gearing in said main chamber and said chambers containing a lubricant for the gearing, means for supplying lubricant to said initial gear chamber, and means for maintaining a lubricant level in said initial gear chamber below the bottom of the motor power shaft including certain gears in said initial gear chamber driven by said power shaft and throwing lubricant, and means for receiving the lubricant so thrown and conveying it into the main gear chamber, said lubricant receiving and conveying means including a spout in the same vertical plane with the lubricant throwing gears and adjacent the top of said housing.
5. In an apparatus of the character described, a casing having a chamber in which a power shaft is disposed, a compartment into which said shaft projects and containing intermeshing gearing driven by said shaft and a second compartment containing gearing driven by said first mentioned gearing, said compartments containing a lubricant for the gearing, means permitting a restricted flow of lubricant from said second compartment to said first compartment, and means for precluding the entry of lubricant from said first mentioned compartment to said chamber along said power shaft including means for automatically discharging lubricant from said first mentioned compartment to said second mentioned compartment and having lubricant discharge means adjacent the tops of said compartments.
6. In an apparatus of the character described, a casing having a chamber in which a power shaft is disposed, a compartment into which said shaft projects and containing a gearing driven from said shaft, a second compartment containing gearing driven from said gearing, said compartments containing a lubricant for the gearing, means permitting a restricted flow of lubricant from said second compartment to said first compartment, and means for maintaining the level of the lubricant in said first mentioned compartment below the bottom of the power shaft including means disposed in the same vertical plane with the gears in said first mentioned compartment for receiving the lubricant thrown by said latter gears and conveying it into said second mentioned compartment.
7. In an apparatus of the character described, the combination of a driving motor enclosed in a housing, a main gear chamber
- into which the end of the motor shaft extends and which contains a train of intermeshing reduction gearing driven from said motor shaft and a lubricant, a lubricant containing compartment partitioned off from the gear chamber and arranged to enclose the end of the motor shaft and the initial gear elements of the aforesaid train, means for supplying lubricant to said compartment, and means for automatically maintaining the lubricant level in said compartment below the lowest point on said motor shaft.
8. In an apparatus of the character described, the combination of a driving motor enclosed in a housing, a main gear chamber into which the end of the motor shaft extends and which contains a train of intermeshing reduction gearing driven from said motor shaft and a lubricant, a lubricant containing compartment partitioned off from the gear chamber and arranged to enclose the end of the motor shaft and the initial gear elements of the aforesaid train, means for permitting a restricted flow of lubricant from said chamber to said compartment, and means for automatically maintaining the lubricant level in said compartment below the lowest point on said motor shaft and including means associated with the compartment aforesaid for returning lubricant received therein to the main gear chamber.
9. In an apparatus of the character described, the combination of a driving motor enclosed in a housing, a main gear chamber into which the end of the motor shaft extends and which contains a train of intermeshing reduction gearing driven from said motor shaft and a lubricant, a lubricant containing compartment partitioned off from the gear chamber and arranged to enclose the end of the motor shaft and the initial gear elements of the aforesaid train, means permitting a restricted flow of lubricant from said gear chamber to said compartment, and means for automatically maintaining the lubricant level in said compartment below the lowest point on said motor shaft, the initial gear elements located in the compartments aforesaid being so arranged that by their rotation they act to discharge lubricant, said automatic means including a transfer device adapted to receive the lubricant so discharged and return the same to the main gear chamber.
10. In an apparatus of the character described, the combination of a driving motor enclosed in a housing, a main gear chamber into which the end of the motor shaft extends and which contains a train of intermeshing reduction gearing driven from said motor shaft and a lubricant, a lubricant containing compartment partitioned off from the gear chamber and arranged to enclose the end of the motor shaft and the initial gear elements of the aforesaid train, means

- for restricting access of lubricant along said motor shaft to the motor, means permitting a restricted flow of lubricant from said gear chamber to said compartment, and means for automatically maintaining the lubricant level in said compartment below the lowest point on said motor shaft, the initial gear elements located in the compartments aforesaid being so arranged that by their rotation they act to discharge lubricant, said automatic means including a transfer device adapted to receive the lubricant so discharged and return the same to the main gear chamber.
11. In an apparatus of the character described, a motor housing in which a motor having a power shaft is disposed, a gear housing adjacent said motor housing and having a vertical transverse wall abutting against the adjacent end of said motor housing and a lubricant containing compartment in said gear housing extending transversely along said transverse wall part way across said gear housing, said motor power shaft extending into said compartment, a second larger lubricant containing compartment extending transversely along the side of said first compartment and then rearwardly toward said vertical transverse wall, there being a vertical longitudinally extending partition between said compartments, intermeshing gearing driven by said motor power shaft and contained in said first compartment, intermeshing gearing driven by said gearing and contained in said larger compartment, means permitting a restricted flow of lubricant from said large compartment to said first compartment, and means for automatically maintaining the lubricant level in said first compartment below the lowest point on the motor power shaft, the intermeshing gearing in said first compartment being so arranged that by their rotation they act to discharge lubricant, said automatic means including a lubricant spout carried by said vertical partition between said compartments for receiving lubricant discharged by said gears and returning the lubricant to said large compartment.
12. In an apparatus of the character described, a gear housing having a main gear containing compartment and an initial gear containing compartment, and a lubricant contained in said compartments, the gears in said initial compartment driving the gears in said main compartment, means for permitting a restricted flow of lubricant from said main compartment to said initial compartment, and means conveying the lubricant from the initial compartment back to the main compartment to maintain automatically the lubricant level in the initial compartment below the level of the lubricant in the main compartment.
13. In an apparatus of the character de-

scribed, a gear housing having a main gear containing compartment and an initial gear containing compartment, and a lubricant contained in said compartments, the gears in said initial compartment driving the gears in said main compartment, means for permitting a restricted flow of lubricant from said main compartment to said initial compartment, and means conveying the lubricant from the initial compartment back to the main compartment to maintain automatically the lubricant level in the initial compartment below the level of the lubricant in the main compartment by the gears splashing the same, a spout for receiving the lubricant so splashed and a duct for conducting lubricant from said spout back to the main compartment.

14. In an apparatus of the character described, a motor housing containing a motor having a power shaft, a gear casing having a main gear chamber adjacent said motor housing and containing lubricating oil, an intermediate chamber between the motor housing and the gear casing and into which said motor power shaft projects and in which the lubricating oil leaking from the main gear chamber of the gear casing is collected, and devices located in the intermediate chamber for automatically discharging oil from said chamber so that the oil level in the intermediate chamber is kept below the motor shaft.

15. In an apparatus of the character described, a motor housing containing a motor having a power shaft, a gear casing having a main gear chamber adjacent said motor housing and containing lubricating oil, an intermediate chamber between the motor housing and the gear casing and into which said motor power shaft projects and in which the lubricating oil leaking from the main gear chamber of the gear casing is collected, and devices located in the intermediate chamber for automatically discharging oil from said chamber so that the oil level in the intermediate chamber is kept below the motor shaft and including a discharge device which returns the oil collected from the intermediate chamber directly back to the main gear chamber.

In testimony whereof I affix my signature.
LEON E. SIMMONS.
